UNITED STATES PATENT OFFICE.

BENJAMIN FRANKLIN MOSS, OF BISBEE, ARIZONA.

PUMP-PISTON.

1,333,211.

Specification of Letters Patent.

Patented Mar. 9, 1920.

Application filed August 14, 1919. Serial No. 317,508.

To all whom it may concern:

Be it known that I, BENJAMIN F. Moss, a citizen of the United States, residing at Bisbee, in the county of Cochise and State 5 of Arizona, have invented new and useful Improvements in Pump-Pistons, of which the following is a specification.

This invention relates to pumps, particularly to those of the reciprocatory type, 10 and has for its object the provision of a novelly constructed pump piston including a leather cup washer within which is disposed a split spring ring which bears resiliently outwardly against the washer and 15 causes the washer to engage the periphery of the pump barrel closely so as to form a leak-proof contact whereby the pump thus equipped will be highly efficient and whereby the wear on the cup washer will be automatically taken up.

An important object is the provision of a pump in which the barrel is provided adjacent its upper end with a pair of air inlet openings which admit air into the barrel 25 after the piston has passed by the openings on its upstroke.

An additional object is the provision of a pump which will be simple and inexpensive in manufacture and assembly, highly 30 efficient in use, durable in service, and a general improvement in the art.

With the above and other objects and advantages in view, the invention consists in the details of construction to be hereinafter 35 more fully described and claimed, and illustrated in the accompanying drawing in which—

Figure 1 is a side elevation of a pump constructed in accordance with my invention, a portion thereof being broken away 40 and in section, and

Fig. 2 is a sectional view on a larger scale through the lower portion of the pump barrel and also through the piston.

Referring more particularly to the drawing, I have shown a pump formed of a base member 10 having a threaded recess within which is engaged the lower end of a barrel 11 which is closed at its top by a cap 12 through which is slidably a piston rod 13. A barrel 11 is provided adjacent the cap 12 with openings for the purpose of admitting air. The base member 10 has formed therein an outlet passage 15 which is threaded, 50 as shown at 16, for engagement therein of the nipple on any suitable conducting hose.

The piston comprises a concave washer 17 which is engaged upon a reduced portion 18 formed on the lower end of the piston rod 13. Disposed on the reduced portion 18 60 and engaging against the washer 17 is a leather cup washer 19 within which is disposed a flat washer 20 which is engaged by a spacing sleeve 21 surrounding the reduced extension 18. The spacing sleeve 21 is of 65 such length that it will project beyond the open end of the washer 19 and disposed against this projecting end is a flat retaining washer 22 of slightly less diameter than the internal diameter of the barrel 11. The 70 nut 23 is threaded upon the extremity of the extension 18 and engages the washer 22 for holding the various parts of the piston assembled.

In order that the cup washer 19 may 75 always be urged into close engagement with the barrel, I provide a split spring ring 24 which is disposed within the cup washer and which engages against the side flange thereof, as clearly shown.

In the operation of the pump it will be seen that on the upstroke of the piston a partial vacuum will be formed in the lower end of the barrel until the piston passes the opening 14, whereupon air will be drawn into the 85 barrel through the openings 14. On the down stroke the air will be compressed and will be forced out in advance of the piston through the outlet passage 15. At all times it will be seen that by virtue of the spring 90 ring 24 the cup will be urged firmly into engagement with the internal periphery of the barrel so as to form close contact therewith, which will prevent leakage of air past the piston and which will therefore render the 95 pump highly efficient. While air is spoken of in the operation, it will of course be apparent that liquids of any description may also be pumped.

While I have shown and described the 100 preferred embodiment of my invention it is of course to be understood that I reserve the right to make such changes in the form, construction, and arrangement of parts as will not depart from the spirit of the invention 105 or the scope of the subjoined claims.

Having thus described my invention, I claim:

1. A pump comprising a barrel provided at one end with a base having a discharge 110 passage therethrough and at its other end with a cap having a hole therein, said barrel

being further provided adjacent said cap with air inlet openings, a piston rod disposed within the barrel and slideable through the hole in said cap, a reduced extension on 5 the end of said rod, and a piston on said extension including a concave washer, a leather cup washer engaging against said concave washer and having a flange engaging against the inner periphery of the barrel, a flat 10 washer disposed within and bearing against the circular portion of said cup washer, a spacing sleeve surrounding said extension and engaging said flat washer and projecting beyond the open end of said cup washer, 15 a retaining washer engaging against the projecting end of said sleeve, a nut threaded upon said extension and engaging said retaining washer, and a split spring ring disposed within said cup washer and engaging 20 against the inner periphery of the flange thereof.

2. In a pump including a barrel and a reciprocatory piston rod, a reduced extension on said rod defining a shoulder, a concave washer disposed upon said extension and 25 engaging said shoulder, a leather cup washer disposed against said concave washer and having its flange extending in the opposite direction to the concavity of said concave washer, a flat washer disposed within and 30 bearing against the circular portion of said leather cup washer, a spacing sleeve encircling said extension and engaging said flat washer, a retaining washer engaging the outer end of said spacing sleeve, clamping 35 means on said extension engaging said retaining washer, and a split spring ring disposed within said cup washer and bearing against the inner periphery of the flange thereof.

BENJAMIN FRANKLIN MOSS.
